UNITED STATES PATENT OFFICE.

PETER KRUSE, OF NEW YORK, N. Y., ASSIGNOR TO E. W. BLISS COMPANY, OF BROOKLYN, NEW YORK, A CORPORATION OF WEST VIRGINIA.

MACHINE FOR SEAMING CAN-TOPS.

1,063,700.

Specification of Letters Patent. Patented June 3, 1913.

Application filed March 24, 1911, Serial No. 616,717. Renewed September 24, 1912. Serial No. 722,123.

To all whom it may concern:

Be it known that I, PETER KRUSE, a citizen of the United States, residing in the borough of Brooklyn, county of Kings, city 5 and State of New York, have invented certain new and useful Improvements in Machines for Seaming Can-Tops, of which the following is a specification.

The machine provided by this invention 10 is designed for seaming the heads of round cans, and is particularly adapted for seaming the tops or covers on cans already filled. The can is held stationary, and is seamed by seamers or seaming rolls which revolve 15 around it and which while so revolving gradually close in upon it. The cans to be seamed are in the preferred construction fed onto a conveyer which carries them to a feed disk, whereby the cans are brought successively 20 into position beneath the seamers; the can thus placed is then lifted by a plunger to bring its top into the plane of the seaming rolls and is held there during the seaming operation, after which it is lowered, 25 and by the next movement of the feed disk the finished can is carried out of the machine. The machine while preferably designed and adapted for the performance of these functions, is nevertheless adaptable 30 to other uses as will be made apparent.

The complete machine in its preferred form is shown in front elevation in Figure 1 and in side elevation in Fig. 2, the latter view being partly a vertical section. Fig. 35 3 is a plan of the feeding means, the view being partly a horizontal section; Fig. 4 is a horizontal section showing the means for turning the can feed disk; Fig. 5 is a vertical section of the seaming rolls and their 40 connected parts in the planes of the lines 5-5 in Figs. 6 and 7; Fig. 6 is a plan of Fig. 5 partly in horizontal section; Fig. 7 is a plan at a lower level showing the seaming rolls, the view being partly in horizontal 45 section on the line 7 in Fig. 5; Fig. 8 is a perspective of one seaming roll with its arm, spindle and controlling shoe; Fig. 9 is a front view of the cam and slide for raising and lowering the ring which operates 50 the seaming rolls; Fig. 10 is a plan of the cover-feed all lower parts not pertaining thereto being omitted to avoid obscurity; Figs. 11, 12 and 13 are internal sections of the cover-feed in successive positions.

55 Referring to the drawings, A designates

any suitable frame or standard for supporting the operative parts, being shown as an upright frame providing bearings for the rotative shafts and slideways for the sliding parts, as will appear. In the preferred construction shown, power is applied to a horizontal shaft B through fast and loose pulleys a' or otherwise, and from a pulley b on this shaft a belt D is carried over guide pulleys d d to a pulley e on a vertical 60 shaft C, whereby the latter shaft is driven either at the same speed as the driving shaft or at a different speed as desired. The shaft C is hollow, and through it passes a stationary rod E fixedly clamped in a 65 bracket e on the frame A at its upper end, while the lower end of the rod carries a pad or disk F against which the top of the can is to be pressed and held during the seaming. The lower end of the tubular shaft C 70 carries a head or disk G which forms a bearing for the spindles of the seamer rolls.

The construction of the seamers is best shown in Figs. 5, 6, 7 and 8. The seamer rolls H are carried each on a stud h fixed in 75 an arm f which is mounted on the lower end of a spindle g, the upper end of which carries a controlling arm i acted on by a seamer-actuating shell J. The arm i carries a stud i' 80 on which is hung a shoe or runner I, all as clearly shown in the perspective view Fig. 8. The shoes I I are received within the internally-coned shell J. Preferably the stud g is squared at its lower end, and between this squared end and the arm f is a bushing e' 85 fitted on this squared end and fastened by a pin e² or otherwise; the bushing has a lug e³ received between two set-screws g' g' on the arm f, so that by adjusting these screws the arm f may be swung around the axis of the 90 spindle g to carry the roll H toward or from the center of the can, and thereby to regulate the thickness of the seam, or adjust the seaming-roll to the exact diameter of the can. For double seaming it is preferable to 95 use two pairs of seaming rolls H H, one pair being arranged diametrically opposite to perform the first part of the seaming operation, while the rolls H' H' of the other pair, which intervene and are opposite each other (see Fig. 7), perform the final part of the seaming operation; the shoes I' I' which control these rolls are mounted like the shoes I I, except that they are set somewhat lower. 100 The seaming rolls are caused to approach 105 110

the can (q, Fig. 7) while revolving around it, by means of a downward movement of the shell J, so that its coned inner surface j forces the shoes I I' inward. The shoes I I by being set higher than the shoes I' I' are first acted upon and forced inward as the shell moves downward, so that the primary seaming rolls H H move inward first to perform the first part of the seaming operation; then as the shell J moves farther down the secondary or finishing rolls H' H' come into action; at the instant when the primary rolls H complete their work their shoes I I pass beyond the cone surface j and begin (see I, Fig. 5) to ascend a parallel or cylindrical surface j' (or this might be an expanding surface if it is desired to permit the primary rolls to move outward and disengage the seam); the shoes I' may engage only the coned surface j, or may in turn run against the surface j'; when the seaming operations have been completed the shell J moves upward, thereby permitting the shoes I I' and rolls H H' to move outwardly by the centrifugal tendency, thereby freeing the finished can. Thus the shell J which by its vertical movement controls the inward and outward movements of the seamers, necessarily executes one downward and then one upward movement to each can that is seamed, followed by a dwell of sufficient duration to permit the seamed can to be removed and a new can to be brought into place. For imparting this relatively slow movement the driving shaft B drives through reducing gearing (for example a worm k and worm-wheel k') a shaft K carrying a cam K' the cam-groove of which engages a roller l (Fig. 9) on a vertically moving slide L movable in ways in the main frame A, which slide at its upper part is formed with a bracket L' to which the coned shell J is connected. The shaft K turns once to each seaming operation. The shell J might be non-rotative, and the shoes I I' slide around within it; or to diminish friction the shoes might be replaced by rollers; but preferably the shell J is made to rotate with the shoes, being carried with them frictionally, and to diminish friction between the shell and the bracket L' ball bearings are interposed. A suitable construction is that shown, where the shell is fastened to a cap J' having a hub turning freely in the bracket L', and with two interposed series of balls c' and c'' above and below the bracket to transmit the vertical thrusts.

The shaft K drives through miter gears m m a vertical shaft M which drives the feed mechanism. On the upper end of this shaft is fixed the crank disk P of a Geneva stop movement, its crank p driving a star wheel Q on a shaft Q' which carries a notched feeding disk R, all as best shown in Figs. 2 and 4. Beneath the disk R is a ver-

tically movable plunger S in line with the shaft C. The can is pushed over the top of a table T onto the plunger S, which is then raised to bring the can into the seaming position. This movement is derived from the shaft M which carries a cam S' (conveniently formed in one part with the crank disk P), the cam surface of which acts on a roller t on a lever t' the long arm of which engages an upright spindle s (or other sliding frame) carrying the plunger S. The plunger is thus held elevated during the entire seaming operation, at the end of which its roller t runs off the cam incline s' and lowers the plunger, which remains down while the crank p is turning the star wheel to carry off the seamed can and feed into place a new can, whereupon the incline s'' lifts the roller t and again elevates the plunger for a new seaming operation.

The cans to be seamed are fed by the operator onto a feeding rack or chute U, along which they are caused to travel by an endless chain V turning on sprocket wheels v v'. This chain may be suitably driven, preferably from the shaft K, through chains w w' carried over suitable sprockets. The chain V carries the cans (q q, Fig. 3) onto the table T and into the successive notches in the feed disk R. This disk turns intermittently and carries the successive cans onto the plunger S.

For feeding the cans out of the machine, an inclined chute W is provided, so located that the feed disk R pushes the cans off the table T and into this chute, down which they may slide by gravity. One side of this chute is extended as a rim around the table T, as shown in Fig. 3, to prevent the accidental escape of the cans while being fed by the disk R.

The machine as thus far described is adapted to receive and close cans the tops or covers of which are placed upon them by hand. But to make the machine more completely automatic it is desirable to provide the machine with means for applying the covers to the cans. For this purpose a second feed disk X is mounted on the shaft Q' and is adapted to feed the covers from a reservoir or stack Y to positions above the successive cans, so that as each can is lifted by the plunger S, it finds its cover in concentric position above it and enters the cover and lifts it against the disk F into position for the seaming-rolls to unite the cover to the can. The stack Y is a suitably-supported stationary upright tube or skeleton frame in which the covers are placed and loosely held. The disk X has a series of holes fitted with bushing rings y y which stop successively beneath the stack, each ring having a recess y' into which the lowermost cover q' may partly enter (see Fig. 11) so that at the next movement of the disk this

cover is carried away by the ring so that the next cover may descend onto the disk, to enter the next ring in its turn. The underside of each ring y is coned at y^2 so that when the movement of the disk has brought the cover directly over the can (see Fig. 12), this coned surface will serve as a guide for the rising can, to cause the can to enter the ring, and receive and lift the cover (see Fig. 13), so that the cover and can will be brought in correct, concentric position up against the disk F and within the revolving seaming rolls H H. The opening through the ring y is too small to admit the cover, but is large enough to admit the flanged can body, and to permit the seamed can to pass down through it. To assist in freeing the seamed can from the disk F a spring-pressed push-out pad F' is provided, the stem of which seats against a spring housed in the stationary shaft E, (see Fig. 5.)

The machine is designed to be readily adapted to varying sizes of cans, whether the variations be in height or diameter. For adjusting the machine for different heights of cans, the feed mechanism is carried by a special frame or bracket A', which may be fastened higher or lower on the frame A; and the shaft M is made in two parts, the one sliding within the other and splined together. The cover-feed disk X may be set higher or lower relatively to the shaft Q' to restore it to the proper level after any adjustment of the height of the bracket A'. The feed chute U has side guide bars u fastened adjustably at u' , so that they may be moved toward or from the center to accommodate cans of varying diameters. For adjusting it to cans of varying heights, the chute U may be raised or lowered together with the table T and other parts of the feed mechanism described, the chains w adapting themselves to this movement since the axes of their sprockets are connected through links x x' . The outer end of the feed chute U may be supported by a telescopically-adjustable support U'. The can-feed disk R is made adaptable to cans of varying diameters by making its notches adjustable; and for this purpose the disk carries an auxiliary disk R' fastened to it by a set-screw r and having projections r' entering the notches in the disk R, so that by turning the disk R' to varying positions the effective width of the can-receiving notches may be varied as desired. The set-screw r may engage an arc-shaped slot in one of the disks, or preferably holes r^2 registering in different positions may be provided for the varying sizes of cans to be handled. To prevent the operators' clothing being caught by the disk R R' it is desirable to extend a guard rail or curved bar r^3 around it, as shown in Fig. 3. For adapting the cover-feed disk X to feed covers of different di-

ameters its bushing rings y y are made detachable so that they may be removed and replaced by rings having openings adapted in size to the covers to be used. For adjusting the seamers to cans of varying diameters (where the adjustment exceeds the capacity afforded by the screws g'), it is only necessary to provide a series of bushings e' , having their lugs e^3 projecting at different angles relatively to the squared end of the spindle g , so that by substituting a different bushing the arm f is projected to a different angle, and its seaming roll H or H' is brought to a different distance from the axis of rotation. For an extreme adjustment the shell J may be removed and replaced by a larger or smaller shell; and if necessary a larger or smaller head G may be provided.

The machine described is very simple in construction, has few working parts, operates automatically and with great rapidity in the seaming of filled cans, which are held stationary during the seaming operation; and is easily adjusted to receive cans of varying sizes.

The machine may be used for seaming the bottoms of empty can bodies by presenting them to it in inverted position.

The primary and secondary seaming rolls are best arranged in pairs and diametrically opposite, in order to equalize the pressure during the seaming operation, but this is not essential since except for the disadvantage of an unbalanced or one-sided pressure, one roll of each pair could be omitted.

To guard against the possibility that any of the covers g' might drop through the openings in the bushings y , due to the clearance being necessarily very small, and because of some irregularity in the punching of the covers, any suitable stop may be provided to constitute a temporary false bottom in the bushing. A convenient construction is that shown in Figs. 10 and 11, where a leaf spring Z (shown in dotted lines in Fig. 10) is fastened to a bracket Z', and is arranged to press upwardly against the under side of the disk X, so that in each stopping position thereof it will enter partly within the opening in the bushing directly beneath the reservoir Y, as shown in Fig. 11. As the disk X turns, it first starts the lowermost cover out from under the reservoir, after which the edge of the bushing strikes the spring Z and presses it down out of the way. If any cover should be small enough to fall through the opening, it will strike the spring Z and be upheld.

The can-feeding means, cover-supplying and feeding means and cover-applying means herein shown and described are not claimed in this application, but are claimed in my application Serial No. 722,252, filed September 25, 1912.

I claim as my invention:—

1. A can seaming machine comprising a revolving seamer head, upright oscillatory seamer spindles carried thereby having lower arms carrying seamers and upper controlling arms, an operating shell engaging said upper arms, said shell free to rotate with said arms, and means for advancing said shell during the seaming operation to force the seamers in against the can while they revolve around it, and for subsequently retracting said shell to permit the seamers to move outward and free the seamed can. 5
2. A can seaming machine comprising a revolving seamer head, upright oscillatory seamer spindles carried thereby having lower arms carrying seamers and upper controlling arms, a shell internally engaging said upper arms, free to rotate with said arms, and having a cam portion adapted to displace said arms inward to force the seamers in against the can while revolving around it, and a portion beyond said active portion adapted to permit the seamers to move idly, and means for advancing and retracting said shell. 15
3. A can seaming machine comprising a revolving seamer head, upright oscillatory seamer spindles carried thereby having lower arms carrying respectively primary and secondary seamers, and upper controlling arms, an operating shell engaging said upper arms, and means for advancing and retracting said shell, said controlling arms engaging the shell at different levels, and the shell and arms relatively arranged and adapted whereby during the advance of said shell it forces first the primary seamers and afterward the secondary seamers in against the can, and during the retraction of said shell the seamers are released in reverse order to free the seamed can. 30
4. A can seaming machine comprising a revolving seamer head, upright oscillatory seamer spindles carried thereby having lower arms carrying seamers and upper controlling arms carrying shoes, an operating shell engaging said upper arms rotatably mounted so that it may turn with said head, and means for advancing said shell during the seaming operation to force the seamers in against the can while they revolve around it, and for subsequently retracting said shell to permit the seamers to move outward and free the seamed can. 45
5. A can seaming machine comprising a revolving seamer head, seamer spindles carried thereby having lower arms carrying seamers and upper controlling arms carrying shoes, a rotatably-mounted shell engaging said upper arms having an internal cam surface in contact with said shoes, and means for advancing said shell during the seaming operation to force the seamers in against the can while they revolve around 60
- it, and for subsequently retracting said shell to permit the seamers to move outward and free the seamed can. 6. A can seaming machine comprising a revolving seamer head, seamer spindles carried thereby having lower arms carrying respectively primary and secondary seamers and upper controlling arms carrying shoes, those of the primary seamers being set higher than those of the secondary seamers, an operating shell having internal cam surfaces engaging said shoes, and means for advancing said shell during the seaming operation to force first the primary seamers and, afterward the secondary seamers in against the can while revolving around it, and for subsequently retracting said shell to permit the seamers to move outward and free the seamed can. 70
7. A can seaming machine comprising a revolving seamer head, seamer spindles carried thereby having lower arms carrying respectively primary and secondary seamers and upper arms carrying shoes, those of the primary seamers having their engaging faces higher than those of the secondary seamers, a shell internally engaging said shoes having an active portion inclined so that as the shell is advanced it displaces said shoes inward to force the successive seamers in against the can while revolving around it, and a portion adapted to permit the shoes of the primary seamers to move idly while the secondary seamers are in operation, and means for advancing and retracting said shell. 80
8. A can seaming machine comprising a revolving seamer head, spindles carried thereby having lower arms carrying seamers, and upper controlling arms, an operating shell having internal cam faces engaging said upper arms, means for advancing and retracting said shell, and adjusting means whereby the seamers may be set outwardly or inwardly relatively to said upper arms. 90
9. A can seaming machine comprising a revolving seamer head, seamer spindles carried thereby having lower arms carrying seamers and upper arms carrying shoes, an internally-coned shell engaging said shoes, means for advancing and retracting said shell, and adjusting means whereby the seamers may be set outwardly or inwardly relatively to said shoes. 100
10. A can seaming machine comprising a revolving seamer head, seamer spindles carried thereby having lower arms carrying seamers and upper controlling arms, an internally-coned shell engaging said upper arms, means for advancing and retracting said shell, and adjusting means for said seamers comprising a projection and an adjusting screw whereby the lower arms may be displaced relatively to the upper arms. 110
11. A can seaming machine comprising a 120
12. A can seaming machine comprising a 125
13. A can seaming machine comprising a 130

- revolving seamer head, seamer spindles carried thereby having lower arms carrying seamers and upper controlling arms, an operating shell engaging said upper arms, and means for advancing and retracting said shell; one of said arms being adjustable relatively upon the seamer spindle to vary the positions of the seamer and adapt it to cans of different diameter.
- 10 12. A can seaming machine comprising a revolving seamer head, seamer spindles carried thereby having lower arms carrying seamers and upper controlling arms, means for controlling said upper arms, and adjusting means for a seamer comprising a detachable bushing between the spindle and one of said arms, with means for fixedly uniting it to the spindle and means for angularly adjusting the arm relatively to said bushing.
- 15 13. A can seaming machine comprising a revolving seamer head, seamer spindles carried thereby having lower arms carrying seamers and upper controlling arms, means for controlling said upper arms, and adjusting means for a seamer comprising a de-
- 20 tachable bushing between the spindle and one of said arms, with means for fixedly uniting it to the spindle, said bushing having a projection and an adjusting screw on the 30 arm engaging said projection for angularly displacing the arm.
- 25 14. A can seaming machine comprising a revolving seamer head, seamer spindles carried thereby having lower arms carrying seamers and upper controlling arms, means for controlling said upper arms, and adjusting means for a seamer comprising a detachable bushing between the spindle and lower arm, with means for fixedly uniting 35 it to the spindle, said bushing having a projection entering a recess in the arm, and the arm having adjusting screws engaging said projection between them.
- In witness whereof, I have hereunto 40 signed my name in the presence of two subscribing witnesses.
- 45 PETER KRUSE.
